UNITED STATES PATENT OFFICE

EDWARD J. VON PEIN, OF DAYTON, OHIO, ASSIGNEE, BY MESNE ASSIGNMENTS, TO THE NATIONAL CASH REGISTER COMPANY, OF DAYTON, OHIO, A CORPORATION OF MARYLAND

CASH REGISTER

Application filed April 26, 1923. Serial No. 634,739.

This invention relates to cash registers, and particularly to improvements in the type of machine shown in applicant's Letters Patent of the United States, No. 1,555,534, 5 granted September 29, 1925.

One of the objects of this invention is to provide novel means adapted to be operated as a preliminary to an operation of the machine, to place the machine in condition to receive the entry of items and print the same, or to print a sub-total or a grand total; and to provide an interlocking mechanism to prevent movement of the novel means out of its position of adjustment during either a sub- 15 total or total printing operation.

Another object of this invention is to provide counting devices to count the number of times totals and sub-totals are printed.

It is also an object to provide a record strip wide enough to receive, in addition to the printed items and totals, written memoranda, such record strip being mounted upon a movable carrier which brings the last printed item into view.

Another object is to provide interlocking mechanism which prevents an operation of the total printing mechanism and the counting devices during an operation of the item entering means.

Another object is to provide locking means controlling the reading and resetting of the totalizer.

Still another object is to provide means for oscillating the record strip carrier by either the item entering means or the total printing means and independent of each other.

With these and incidental objects in view, the invention consists of certain novel features of construction and combinations of parts, the essential elements of which are set forth in appended claims, and a preferred form or embodiment of which is hereinafter described with reference to the drawings which accompany and form part of this specification.

Of said drawings:

Fig. 1 is a plan view of part of the machine.

Fig. 2 is a transverse section taken on the line 2—2 of Fig. 1.

Fig. 3 is a detail view, partly in cross section, of the totalizer shown in Figs. 1 and 2.

Fig. 4 is a fragmentary portion of the autographic strip.

Fig. 5 is a detail view showing the device 55 for coupling the driving mechanism with the totalizer turn-to-zero mechanism.

Fig. 6 is a side elevation of the printer.

Fig. 7 is a detail view of the mechanism for reversing the order of the printing wheels.

Fig. 8 is a section taken on line 8—8 of Fig. 7.

Fig. 9 is a detail view showing the pinions on the printing wheel sleeves for reversing the order of the printing wheels.

Fig. 10 is a transverse section taken on line 10—10 of Fig. 1, looking in the direction of the arrows.

Fig. 11 is a plan view of the printer driving shaft and the mechanism for rocking the 70 autograph platen.

Fig. 12 is a detail view of the mechanism for rocking the autograph platen during a total printing operation.

Fig. 13 is a detail view showing the mechanism for operating the main driving shaft during adding operations.

Fig. 14 is an end view of the printer driving shaft mechanism, together with a view of a portion of the total printing impression 80 hammer.

The machine to which the present invention is applied, includes the usual amount keys, means for indicating the amount set up by the keys, means for entering said amount in a 85 totalizer and for printing the same, and means for printing the total of the amounts entered. To such a machine mechanism is provided for counting the number of times the totalizer is read and also reset, for controlling "read" 90 and "reset" operations of the totalizer, and for moving the paper for displaying the last printed record.

Referring to Figs. 1 and 2, the amount keys 25, arranged in denominational groups as usual, are pivoted on a transverse rod 26 carried by the side frames of the machine, and at their rear ends are notched to cooperate with a lip on a key coupler 27 for purposes well known in the art.

The rear ends of the keys are extended to cooperate with indicators 28, and also with pivoted key stops 29 which prevent a simultaneous depression of a plurality of keys in a single denominational group.

Differentially notched arms 30, connected to the rear ends of the keys, are provided with notches 31 for engaging rods 32 carried by registering frames 33, supported on a shaft 34. There is a registering frame for each denominational group of keys 25, and each of the frames has operatively connected to it a registering segment 35. These segments are grouped as shown in Fig. 1 with the right hand one directly attached to the frame 33 and the others connected with their respective frames by the shaft 34 and pinions 36 and 37 secured to shafts 38 and 39 respectively. The notches in the arms 30 are located to transmit amounts of movement to the actuators proportionate to the number of units represented by the keys to which the arms are connected.

The registering segments or totalizer actuators 35 are normally in mesh with gears 40 which are operatively connected with the item type wheels 41 (Figs 1 and 6) by a tube line 42 to set up the amounts represented by the keys depressed. Referring to Figs. 7, 8 and 9, secured to the right hand end of the tube line 42 are gears 43 which mesh with pinions 44 mounted on rods 45 carried by plates 49, each provided with a hub 50 supported by the right hand side frame of the machine and a printer frame 66. These pinions 44 are sleeved to companion pinions 46 which mesh with gears 47 secured to the left hand end of a tube line 48 to the right hand end of which the type wheels 41 are attached. This method of connecting the telescopic tubings for printing wheels is employed for the purpose of bringing the printing wheels in proper order to print correctly on the record strip.

The key coupler 27, before referred to, is pivotally mounted in the side frames and rests upon the rear ends of the keys from which it receives its movement. The right hand end of the key coupler (Fig. 13) carries a roller 55 which cooperates with a slot in a double rack 56 guided on a stud 57 projecting from the frame of the machine. The opposing teeth of the rack 56 are adapted to be meshed alternately with a gear 58 on a cam shaft 59 to move the shaft in a counter-clockwise direction. The engagement of the teeth with the gear is effected by a spring 60 and a spring drawn arm 61, and is maintained by a flange 62 on the rack and a flange 63 on the machine frame, all operating in the usual and well-known manner.

The cam shaft 59 (Fig. 10) extends through the right hand side frame. A cam 64 fixed to this shaft cooperates with a spring pressed pivoted impression hammer supporting arm 65 which is offset to extend through an open-

ing in a printer frame 66 (Fig. 1) into operative relation with the item type wheels 41 (Fig. 6). By means of this mechanism an impression is taken from the item type wheels upon an autographic record strip 67 (Figs. 1, 4 and 6) during each item entering operation.

The autographic record strip 67 is supported on an oscillating frame 71 (Figs. 1 and 6) pivoted on a stud 72 projecting from the side frame of the machine. This oscillating frame is moved first clockwise to place the next impression receiving portion of the paper in alignment with the type wheels to receive an impression therefrom, and then counter-clockwise to place the last received impression in position to be read through the opening in the casing 73. In item printing operations the oscillating frame 71 is operated by the key coupler which is provided on its right hand end with a trunnion 74 (Fig. 10) extending through the printer frame. An arm 75 secured to the trunnion carries a pivoted block 76 engaged by a bifurcated arm 77 secured to a sleeve 78 (Fig. 11) freely mounted on the stud 72. This sleeve is clutched to a companion sleeve 79 to which is secured an arm 80 (Figs. 6 and 11) having a slot 81 through which a pin 82 passes to engage a notch in an arm 83 and cause the arm to move in unison with the arm 80. This arm 83 is secured to a sleeve 84 to which is secured the paper supporting frame 71. The pin 82 is carried by a pitman 85 actuated by the total printing mechanism to disconnect the paper supporting frame operating mechanism from the item entering mechanism during a total printing operation which will hereinafter be described.

The paper 67 (Fig. 6) is fed from a supply roll 100 over the top of the supporting frame 71 and on to a receiving roller 101. When an item is printed the paper is fed forwardly by a pawl 102 engaging a ratchet wheel 103 as the supporting frame 71 moves clockwise. The usual spring actuated pawl 104 prevents a retrograde movement of the receiving roller. The pawl 102 is pivotally mounted on a lever 105 which is provided with a slot engaging a stud 106 supported in the printer frame 66. The upper end of the lever 105 carries a pin 107 which enters a slot 193 in a bracket 108. The paper can be fed independently of an operation of the machine by moving the lever 105 in a counter-clockwise direction with the pin 107 traveling in the slot 196 in the bracket 108. By this feeding operation the printed total is brought into reading position. A spring tension plate 109 bearing against the supply roll 100 maintains the proper tension on the paper to keep it taut.

An inking ribbon 115 passes between the type carriers and the paper, over guide pins 120

and partly around a feed roller 116 which is rotated by the usual pawl and ratchet device. The ribbon feed pawl 117 is carried on an oscillating lever 118, connected by a link 119 to the paper supporting frame 71. The ribbon has cooperating therewith the usual tension roller 120 which is well known in the art.

5 The amounts represented by the keys depressed are also entered in a totalizer mounted in a frame 121 (Figs. 2 and 3) pivotally supported on pins 122 mounted in brackets projecting rearwardly from a front cross bar 123 secured to the side frames.

10 The totalizer elements (Figs. 2 and 3) include pinions 124 rigid with gear wheels 125 and ratchets 126 supported on a turn-to-zero shaft 127. The shaft is provided with a groove to cooperate with spring-pressed pawls on the totalizer elements to turn the 15 totalizer to zero in the usual manner.

15 The totalizer pinions 124 are normally held disengaged from the actuators 35 by a cam 128 on the cam shaft 59, which cooperates with rollers 129 on a lever 130 mounted on a 20 pivot pin 131 on the totalizer frame. The end of the lever 130 contacts a pin 132 on the totalizer frame 121 to rock said frame to engage the pinions 124 with the actuators 35. One of the pins 122 projects through the 25 lever 130 and acts as a means for holding said lever immovable relative to the frame 121, so that said frame may be rocked by the lever 130 to disengage the pinions 124 from the actuators 35. When a key is depressed the 30 cam is rotated clockwise and the totalizer pinions 124 are moved into mesh with the actuators and out of mesh therefrom in a manner well known in the art, and disclosed in United States Letters Patent, Nos. 718,565 35 and 773,060, granted January 13, 1906, and October 25, 1904, respectively, to Joseph P. Cleal.

40 For the purpose of effecting transfers each totalizer wheel is provided with a transfer disk having a trip nose 136 adapted to engage a nose on a transfer trip pawl 137 to move the same out of supporting relation with respect to a transfer pawl 138 which may then move into engagement with the ratchet 126. This pawl is pivotally supported 45 on a transfer lever 139 which is rocked as usual by cams (not shown) on the cam shaft 59, during each item entering operation of the machine.

50 The amount accumulated in the totalizer is ascertained by a printing operation. For this purpose, mechanism is provided for setting up total type wheels 141 (Fig. 6) to print 55 the amount in the totalizer which has stepped disks 142 (Figs. 2 and 3) rigid with gear wheels 143 mounted on a rod in the totalizer frame 121 and meshing with the gears 125 rigid with the totalizer pinions 124.

60 65 The total type wheels 141 (Fig. 6) are lo-

cated to the right of the printer frame 66 and are suitably supported by said frame and a supplemental frame 144. These wheels are connected by a tube line 145 with gears 146 (Fig. 10) in mesh with segments 147 rigidly connected with segment 148 in mesh with segments 149 connected by a tube line 150 (Figs. 1 and 10) with feeler arms 151 adapted to be moved into engagement with the steps on the disks 142 of the totalizer. 70 The tube line is supported by a rod 152 supported in the printer frame and in a bracket 153 mounted on the front cross bar 123. The steps on the stepped disks 142 are so located that the type wheels will be set in 75 accordance with the amount in the totalizer when the feeler arms 151 are moved into contact with said disks.

80 Also integral with the segments 148 are other segments 154 (Fig. 10) which mesh with segmental gear levers 155 provided with hooks 156 supporting the upper ends of tension springs 157 which are also attached to a lever 158. The springs are normally restrained against moving the arms 151 and total type wheels by a lever 159 connected by a link 160 to said lever 158 and having a bar 166 held in contact with the levers 155. The lever 158 is rocked first clockwise and then counter-clockwise by cams 161 secured on a 85 driving shaft 162 driven by a gear 163 (Fig. 14) in mesh with a gear 164 driven by a crank 165 (Fig. 6) or any suitable means. As the lever 158 is moved clockwise the bar 166 is removed from the levers 155 and the 90 springs 157 are permitted to function to set up the total type wheels in accordance with the amount in the totalizer in the manner described in the previously mentioned Von Pein patent, No. 1,555,534.

95 The driving shaft 162 makes one rotation for each total printing operation, being stopped at the end of the rotation by a notched block 170, (Fig. 14) secured to the gear 163, engaging an arm 171 freely mounted on a pin 172 supported by the printer frame 66. Before the shaft 162 can move counter-clockwise it must be given a slight clockwise movement by a reverse movement of the operating crank which permits the arm 171 to be moved 100 counter-clockwise by a spring 173 assisted by a plate 174 engaging an arm 175. Projecting laterally from the arm 175 and through an opening in the arm 171 is a pin 176 to which one end of the spring 173 is attached. As 105 the shaft rotates counter-clockwise the plate 174 is brought into engagement with the lower side of the arm 175 thereby moving the arm clockwise and through the pin 176 cooperating with the upper side of the opening in the arm 171 to cause the arm to move 110 clockwise and engage the notched block 170 to stop the shaft 162 at the end of a complete rotation thereof.

115 120 125 130 Impressions from the total type wheels

are made upon the autographic strip 67 referred to, by an arm 179 (Fig. 6) which carries a platen to print the total shown at the top of the strip in Fig. 4. The arm 179 is pivoted on a stud 180 supported in the printer frame 66 and carries a roller at its lower end cooperating with a cam 182 (Fig. 14) formed in the side of the gear 163.

The paper supporting frame 71 is oscillated during a total printing operation by a cam 183 (Figs. 11 and 12) secured to the driving shaft 162. Cooperating with the cam is a roller 184 carried on a pitman 185 one end of which is connected by a stud to an arm 186 secured to the paper supporting frame. The cam is provided with a slot 187 into which the roll 184 moves when the paper supporting frame is oscillated by the item entering means previously described.

The pin 82 (Fig. 6) which couples the arm 80 with the arm 83 to oscillate the paper supporting frame during an item entering operation as previously described, is moved out of the notch in the arm 83 during the total printing operation, by a cam 188 (Figs. 6 and 11) secured to the driving shaft 162 and cooperating with a roller carried on the pitman 85.

During a total printing operation the ratchet and pawl paper feeding mechanism 102—103 is disabled by a cam 192 (Figs. 10 and 11) secured to the driving shaft 162 and cooperating with a roller carried on a pitman 193 the forward end of which has a slot 194 engaging a pin 195 mounted in the lower end of a downwardly extending arm of the pawl 102 (Fig. 6). The pawl is moved counter-clockwise on its pivot by the arm 192 and pitman 193 so as not to engage the ratchet 103 when the frame 71 oscillates.

The printed total is moved into view after a total printing operation by manually feeding the paper by moving the pin 107 (Figs. 1 and 6) downwardly in the slot 196 formed in the bracket 108. This causes the pawl 102 to engage a tooth in the ratchet 103 and to move the paper receiving roller 101 counter-clockwise. This operation is repeated until the printed total is visible through the opening in the casing 73.

Means are provided for printing reading or sub totals and reset or final totals. In printing reading totals the amount accumulated upon the totalizer is printed upon the autographic strip without resetting the totalizer to zero, while in printing reset totals the totalizer is simultaneously reset to zero.

The total printing is under the control of a slide 197 (Figs. 1 and 6) which has a normal position for entering items on the totalizer, a rear position for reading the total, and a forward position for resetting the totalizer. A handle 198 projecting upwardly from the slide 197 and through a slot in a cover 199 constitutes a manipulative means for posi-

tioning the slide. The manipulation of this slide is under the control of locks 200 and 201 supported in a casing 190 (Fig. 10) carried by a bracket 191 secured to the printer frame 66.

Secured to the handle 198 is a bracket 202 (Figs. 1 and 6) which normally projects between the lock bolts 203 and 204 of the locks 200 and 201 respectively when both lock bolts are in their locked positions, as shown in Fig. 1, thus locking the slide 197 in the normal item entering position, thus locking the total printing mechanism, as will hereinafter be described. Unlocking the lock 200 withdraws the lock bolt 203 permitting the moving of the slide 197 to the "read" position which permits an operation of the total printing mechanism to print on the autographic strip a total of the items accumulated in the totalizer without resetting the totalizer to zero. By unlocking the lock 201 the slide 197 may be moved forwardly to the "reset" position so that a total may be printed and in addition the totalizer automatically reset at zero.

The slide 197 (Figs. 1 and 6) is provided with a downwardly extending arm 205 having a bifurcated end engaging a pin 206 carried by a type carrier similar to the type carrier 141. This type carrier contains two type characters to designate a "read" total and a "reset" total. The total shown in Fig. 4 is a reset total designated by the letter "Z." Any other character may be used to distinguish the different totals.

The slide 197 is supported by pins 210 and 211 projecting laterally from the printer frame 66. Secured to the right hand end of the slide is a curved plate 212, which, when the slide is in normal position, is underneath a flat sided pin 213 (Figs. 5 and 6) projecting from the link 160, to prevent the operation of the total printing mechanism.

Moving the slide to the right or into the "read" position will move the plate 212 away from the pin 213 and permit an operation of the total printing mechanism, and at the same time will disengage a latch 214 (Figs. 5 and 6) from a segment lever 215. This latch is pivoted to the link 160 by a screw stud and has a laterally projecting pin 216 engaging a curved slot 217 formed in the slide 197. A notch 218 in the latch 214 normally engages a pin 219 carried by the segment lever 215.

The plate 212 is so shaped that as the link 160 moves downwardly during the reading operation, the pin 213 travels along the front edge 224 of the plate, thus locking the slide 197 in the "read" position until the operation has been completed.

The segment lever 215 meshes with a partial gear 220 secured to a shaft 221 (Fig. 6). This gear carries a pin 222 which enters a notch 223 in the slide 197 to retain the gear and segment lever in their normal positions

when the latch 214 is disengaged from the pin 219.

Moving the slide to the left or into the "reset" position, withdraws the notch 223 from the pin 222 but maintains engagement of latch 214 with the pin 219 in the segment lever 215. The movement of the slide 197 to the left also moves the plate 212 to the left and away from the pin 213 permitting operation of the total printing mechanism together with the operation of the totalizer resetting mechanism.

As the link 160 moves downwardly during the reset operation, the pin 213 travels along the rear edge 225 of the plate 212, thus locking the slide 197 in the "reset" position until the operation has been completed.

Resetting of the totalizer to zero is effected by actuation of the segment lever 215 which meshes with the partial gear 220 secured to the shaft 221 which freely supports the segments 147, 148 and 154 (Fig. 10). Secured to the shaft 221 on the left side of the printer frame is a segment 226 which meshes with a gear 227 carrying a spring-pressed pawl 228 cooperating with a ratchet 229 integral with a gear 230 in mesh with a gear 231. The gear 231 is secured to a shaft 232 connected by a universal short shaft coupling 233 (Fig. 1) with the turn-to-zero shaft 127 (Fig. 3) of the totalizer. The shaft 127 carries a cam 234 (Fig. 1) which cooperates with an arm 235 connected to a shaft carrying arms 236 (Fig. 3) to raise the transfer pawls 138 during turn-to-zero operations. By means of this mechanism the totalizer is turned to zero during the latter part of the total "reset" operation.

For the purpose of counting the number of times a "read" or a "reset" operation is made, counting devices are provided to be actuated during these operations. These counting devices are the regular step by step counters and are supported by the bracket 191 (Figs. 6 and 10) and are inoperable when the slide 197 is in its normal position.

Counter 237 is actuated during a "read" operation by a lever 238 (Figs. 6 and 10) pivoted on a stud 239 mounted in the slide 197, and having a slot 240 engaging a pin 241 projecting from an oscillating arm 242 secured to the counter actuating shaft. This lever is normally held in contact with a pin 243 projecting laterally from the bracket 191 (Figs. 6 and 10) by a spring 244. The lever 238 is moved clockwise during the total printing operation by a pin 245, carried by the lever 159, engaging a foot 246 on the lever 238, thus operating the arm 242 (Fig. 6) to add "1" on the "read" counter.

The "reset" counter 247 is actuated by a lever 248 (Fig. 10) pivoted on the stud 239 and normally held in contact with the pin 243 by a spring 249. A slot 250 in the lever 248 engages a pin 251 projecting from an oscil-

lating arm 252 (Fig. 6) secured to the counter actuating shaft. The lever 248 has a foot 253, which when the slide 197 is in the "reset" position, will be engaged by the pin 245 and be moved clockwise and actuate the "reset" counter. With the slide in this position the foot 246 on the lever 238 will be out of the path of movement of the pin 245.

Machines constructed in accordance with the disclosures herein may be employed as ordinary itemizing record printing cash registers with provision for memoranda in connection with the item printing. "Read" and "reset" operations of the totalizer being controlled by locks, are ordinarily not available to the operator, the keys for the locks being in the possession of the proprietor or some authorized person.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. The combination of a total printing mechanism, a totalizer resetting mechanism adapted to be operated by said printing mechanism, a slidable control plate adapted in one position to prevent an operation of said printing mechanism and in other positions to permit an operation of said printing mechanism, and means operated by movement of said plate into one of said latter positions to disconnect said resetting mechanism from said printing mechanism.

2. The combination of a total printing mechanism, a totalizer resetting mechanism adapted to be operated by said printing mechanism, a slidable control plate having an aperture and adapted in one position to prevent an operation of said printing mechanism and in other positions to permit an operation of said printing mechanism, and means carrying a projection cooperating with the aperture in said plate for connecting and disconnecting said mechanisms.

3. The combination of a total printing mechanism, a totalizer resetting mechanism adapted to be operated by said printing mechanism, a slidable control plate having an aperture and adapted in one position to prevent an operation of said printing mechanism and in other positions to permit an operation of said printing mechanism, means having a projection cooperating with the aperture in said plate for connecting the resetting mechanism with the printing mechanism and disconnecting said resetting mechanism from said printing mechanism, and means on said plate for locking said totalizer resetting mechanism against operation when it is disconnected from said printing mechanism.

4. The combination of a sub-total and total printing mechanism, a control plate for controlling said mechanism for printing totals and sub-totals, total and sub-total consecutive counters, means carried by said plate for actuating either of said counters as determined by said plate, and means common to the actuating means and operable upon operation of said printing mechanism for operating the selected one of the actuating means.

5. The combination of a sub-total and total printing mechanism, a slideable control plate for controlling said mechanism to print a sub-total or total, sub-total and total consecutive counters, arms for actuating either of said counters pivotally mounted on said plate, means common to said arms to operate either of them during a printing operation, and projections on said arms either of which is adapted to be moved into cooperative relation with said common operating means by said plate to operate the counter appropriate to the character of total printed.

6. The combination of an item entering and item printing mechanism, a totalizer, a sub-total and total printing mechanism, sub-total and total consecutive counters, an adjustable control plate to determine whether the machine is to enter and print items or print a sub-total or total by being adapted when set in one position to prevent an operation of the total printing mechanism and consecutive counters and in other positions to permit operation of the total printing mechanism for total and sub-total printing, means for driving said counters comprising arms carried by said plate and each adapted to drive one of said counters during sub-total and total printing operations as determined by said control plate and actuating means common to said arms for operating the one selected by said control plate during an operation of said printing mechanism.

7. In a machine of the class described, the combination of a totalizer adapted to be reset to zero, means for resetting said totalizer to zero, a counter, means for operating said counter, an operating means for actuating said resetting means and counter operating means, and manipulative means adjustable to prevent the operation of said resetting means and said counter operating means.

8. The combination of item printing means, total printing means, a pivoted paper support, means for moving said support during item printing, and means operable during a total printing operation for rendering said moving means ineffective and for moving said support.

9. The combination of item printing means, total printing means, a pivoted paper support, means for moving said support during item printing, means operable during a total printing operation for rendering said moving means ineffective and for moving

said support, paper feeding means carried by said support, means operable upon movement of said support during item printing, for operating said feeding means, and means for rendering said paper feed operating means ineffective during a total printing operation.

10. The combination of an item printing mechanism, a total printing mechanism, a pivoted paper support, separate means for moving said support during item and total printing operations, means for feeding a record strip carried by said support incident to a movement of said support in item printing operations, and means for rendering said feeding means inoperative as the support is moved during total printing operations.

11. The combination of a sub-total and total printing mechanism; a counter for counting the number of sub-total operations made by said mechanism; a counter for counting the number of total operations made by said mechanism; an actuating device for each of said counters; means common to said devices and carried by said printing mechanism for operating either of the devices upon operation of said printing mechanism; and a slideable member for controlling said printing mechanism so that either a sub-total or total may be printed, said member being connected to both of said devices to move either of them into cooperative relation with the common operating means to cause actuation of either counter depending upon the character of printing operation to be performed.

12. The combination of a total printing mechanism, a totalizer resetting mechanism adapted to be operated by said printing mechanism, a slideable control plate adapted in one position to prevent an operation of said printing mechanism, and in other positions to enable an operation of said printing mechanism, means operated by movement of said plate into one of the latter positions, to disconnect said resetting mechanism from said printing mechanism, and means carried by said plate and adapted to act as a guide for means on the printing mechanism, to prevent movement of the slideable plate during an operation of the printing mechanism on total and sub-total printing operations.

13. The combination of a total printing mechanism, a totalizer resetting mechanism adapted to be operated by said printing mechanism, a slideable control plate adapted in one position to prevent an operation of said printing mechanism, and in other positions to enable an operation of said printing mechanism, means operated by movement of said plate into one of the latter positions to disconnect said resetting mechanism from said printing mechanism, means carried by said control plate and having a concave surface and a convex surface, and means carried by the printing mechanism and adapted to

cooperate with the concave surface to prevent movement of said plate during sub-total printing operations, and adapted to cooperate with a convex surface to prevent movement of the control plate on total printing operations.

In testimony whereof I affix my signature.

EDWARD J. VON PEIN.
